TAPE REEL OR SIMILAR ARTICLE

Clarence E. Bush, Indianapolis, Ind., assignor to Radio Corporation of America, a corporation of Delaware

Filed Jan. 2, 1968, Ser. No. 10,005

Term of patent 14 years

Int. Cl. D14—01
U.S. Cl. D26—14

I claim:

The ornamental design for a tape reel or similar article, substantially as shown.
